United States Patent

Des. 237,003
Patented Sept. 30, 1975

237,003

ELECTRIC LIGHT

Barbara N. Jahandideh, 2324 Kraft Place,
New Orleans, La. 70114

Filed Dec. 10, 1973, Ser. No. 423,342

Term of patent 14 years

Int. Cl. D26—05

U.S. Cl. D48—20 R

FIG. 1

FIG. 2

FIG. 3

FIG. 1 is a side elevation of an electric light, showing my new design,

FIG. 2 is a top plan view thereof on a reduced scale, and

FIG. 3 is a fragmentary bottom plan view on a reduced scale, the shade being omitted for convenience of illustration.

The top of the base is flat and unornamental.

What I claim is:

The ornamental design for an electric light, as shown and described.
